(57) **CLAIM**

The ornamental design for an air-conditioning outlet, as shown and described.

DESCRIPTION

FIG. 1 is a front view of an ornamental design for an air-conditioning outlet showing my new design; the rear view being a mirror image thereto.

FIG. 2 is a left side view of the air-conditioning outlet of FIG. 1.

FIG. 3 is a right side view of the air-conditioning outlet of FIG. 1.

FIG. 4 is a top view of the air-conditioning outlet of FIG. 1.

FIG. 5 is a bottom view of the air-conditioning outlet of FIG. 1; and,
FIG. 6 is a perspective view of the air-conditioning outlet of FIG. 1.

The broken lines and the area within them which illustrate the radiation panel form no part of the claimed design. My design is intended for use as an air-conditioning outlet on an interior ceiling of a room.
